UNITED STATES PATENT OFFICE.

ALBERT SAMUEL, OF PARIS, FRANCE.

ENVELOPE, POSTAL WRAPPER, OR THE LIKE.

Application filed August 19, 1921. Serial No. 493,655.

To all whom it may concern:

Be it known that I, ALBERT SAMUEL, citizen of the French Republic, residing at 1 Rue Pajou, city of Paris, France, have invented new and useful Improvements in Envelopes, Postal Wrappers, or the like, of which the following is a specification.

This invention relates to improvements in envelopes, postal wrappers, and the like and is applicable to those of variable dimensions ordinarily used, the object being to provide an improved wrapper for postal purposes which may be opened very quickly without any tool and without necessitating the insertion of a finger at the corner fold of the envelope. To effect this I provide a special tongue depending from the body of the wrapper which is grasped between two fingers thus allowing said wrapper to be torn open along the wrapper edge, a narrow band running along said edge being varnished or otherwise rendered thicker and facilitating such tearing out, such band being in line with the said tongue or tongues, as hereinafter described and claimed.

In the accompanying drawing:

Fig. 1 shows the improved envelope as sold in the trade, open on the side where the closing flap is provided, in a position parallel to the fold along which the envelope is intended to be torn open, with a narrow band in relief placed opposite to the protruding tongue.

Fig. 2 shows the paper blank as it is cut out to form this improved envelope, the latter being provided with two protruding tongues serving to rip open the envelope, said tongues being placed on each side close to the fold of the closing flap of the envelope.

Fig. 3 is a plan view of a matrix serving to cut out the paper blank by forming it with a protruding tongue on each side of the closing flap.

Fig. 3^a is a section made by $x-x$ of the said matrix.

The paper blank A is intended to form this envelope having one or two tongues a b is cut out by means of a matrix M having

the form shown in Fig. 3. The internal edge of this matrix is notched as at n either on one side only or on both sides at n n' ; the angles o of the said notches are rounded for not tearing the paper during the making of the envelope.

The inner face of the closing flap B of the envelope is covered in a position parallel to the fold c c of said flap with a semifluid substance or varnish applied along the narrow band e which is placed opposite to the protruding tongue a or along the straight line 60 connecting the two protruding tongues a b . The flap B of the envelope is covered, as usually, in the vicinity of its angular edge with a layer of an adhesive material such as glue which occupies a narrow band d parallel to the said edge.

When the envelope or postal wrapper containing documents or pieces of correspondence is being closed and stuck, the protruding tongue a or tongues a b may be, if desired, folded inwardly on the body of the envelope or wrapper.

In order to open this envelope or wrapper without any tool, the user of the envelope only needs to maintain the tongue a or b between two of his fingers and then to exert a pull in the direction of the line c c ; the latter part being reinforced owing to the layer of material e , such a pull causes the flap B to be torn open along a ripping line parallel to the reinforcement band e .

What I claim and desire to secure by Letters Patent is:—

An improved envelope, capable of being opened without necessitating any special tool, the said envelope being provided on its inner face in a position parallel to the line along which the closing flap is folded with a narrow band on which a semi-fluid substance or varnish is applied so as to render the paper thicker, the paper being formed opposite to this narrow band on one side with a protruding tongue.

In testimony whereof I have signed my name to this specification.

ALBERT SAMUEL.
